TOOL FOR EXTRACTING TIE-RODS FROM
CAST CONCRETE

Samuel S. Colt, Orange, N. J.

Application January 14, 1935, Serial No. 1,697

12 Claims. (Cl. 254—31)

This invention relates to a novel tool for withdrawing form tie-rods from cast concrete, for tightening up form holding devices, and for similar uses.

5 This invention has for its principal object to provide a novel and easily manipulated tool for the above-named and similar purposes, wherein means are provided for gripping a form tie-rod end in combination with means for imparting motion to the gripping means to thereby transmit such motion to the tie-rod for loosening and thereupon withdrawing the same from a finished concrete mass, or by so gripping a fixed form tie-rod utilizing the tool movement for pressing home 10 form wall structures to desired assembled relation.

15 The invention has for a further object to provide a novel tool for the purposes described, comprising an abutment means, a frame movable relative to said abutment means, lever means operatively interconnected between said abutment means and frame for producing relative movement therebetween, and a rod gripping means carried by the frame, means being provided for moving the rod gripping means into and out of 20 gripping relation to a rod.

25 Other and more specific objects of this invention, not at this time more particularly enumerated, will be understood from the following detailed description of the same.

30 Embodiments of this invention are shown in the accompanying drawings, in which:—

Fig. 1 is a side elevation of the novel tool according to this invention as applied to a tie-rod, the tie-rod gripping means being shown by full 35 lines in released relation to the rod, and by dotted lines in gripping relation thereto; Fig. 2 is a top plan view of the tool; Fig. 3 is a fragmentary transverse section, taken on line 3—3 in Fig. 1; Fig. 4 is a fragmentary horizontal section, taken on line 4—4 in Fig. 3; Fig. 5 is a longitudinal sectional view of the tool in operative relation to a tie-rod, ready for manipulation; and Fig. 6 is in part a side elevation and in part a longitudinal section showing the operation of the tool 40 for transmitting extracting movement to the tie-rod.

45 Fig. 7 is a fragmentary view showing a modified means for producing relative movement between the abutment means and frame of the tool.

50 Fig. 8 is a fragmentary transverse section through the abutment means showing a sleeve therein for reducing the diameter of its bore to fit small sizes of tie-rods.

55 Similar characters of reference are employed

in the above-described views, to indicate corresponding parts.

Referring to the drawings, the reference character 10 indicates a finished concrete mass and 11 a tie-rod imbedded therein, with an end thereof projecting from said concrete mass. Such tie-rods are employed to hold together in assembled relation the walls of a form in which the concrete mass was cast. After casting of the concrete and ensuing setting or hardening of the same, the 10 form walls are removed, the tie-rods remaining imbedded in the concrete mass. Sometimes the projecting ends of the tie-rods are cut off and the bodies thereof left imbedded in the concrete. This is not desirable, since it involves waste. It is 15 desirable, where possible, to withdraw the tie-rods from the finished concrete so that the same may be used over again. Apparatus for loosening and withdrawing such tie-rods from finished concrete as heretofore provided has not been entirely satisfactory, for the reason that the use and manipulation thereof was frequently difficult and arduous, and operated to so bend and distort the tie-rods, that considerable additional labor and loss of time was involved in straightening the same 20 before they could again be used, all of which offset the economical advantages otherwise attainable by such salvaging of the rods. This novel tool, which is the subject of this invention, has been designed not only with the view of providing 25 a powerful and yet easily manipulated tool for the purpose, but also a tool which so functions in withdrawing the rod that tendency to bending and distortion thereof is avoided.

The novel tool according to this invention comprises an abutment means preferably in the form of a collar or tubular sleeve 12, having an annular lateral flange or footing means 13 at one end thereof. Adjacent to its opposite end, said collar or sleeve 12 is provided with an externally 35 disposed perforate fulcrum ear or lug 14, to which is pivotally attached, by a pivot pin 15, the bifurcate end 16 of a crank-lever 17. Said crank-lever 17 is provided with an outwardly projecting hand-lever 18 for manipulating the same. 40

Pivots attached to said crank-lever 17 is a frame structure comprising side pieces 19 respectively disposed on opposite sides of the crank-lever 17 and connected thereto by a cross bolt 20 which extends through ends thereof and said 45 crank-lever. Integral with thus connected ends of said frame side pieces are downwardly extending arms 21, which straddle and terminate below said collar or sleeve 12. Connected by a cross-bolt 22 between the lower free ends of said 50

55

frame arms 21 is a longitudinally and outwardly extending stationary handle member. This handle member preferably comprises a pair of laterally spaced apart bars 23, between the outer ends 5 of which is secured the attachment lug 24 of a hand or push-piece 25, whereby the latter is affixed to the outer end of the stationary handle member.

Pivotedly mounted on a fulcrum bolt 26 extending between the frame side pieces, at a point intermediate the ends of said frame, is transverse dependent chuck member 27 having an opening 28 therethrough. Formed on the outer face of said chuck member 27 are transverse stop ribs, 10 comprising an upper stop rib 29 above the opening 28 and a lower stop rib 30 below said opening 28. These ribs 29—30 bound a seat against which is seated a hardened steel gripping plate 31 having an opening 32 therethrough, which registers 15 with the opening 28 of said chuck member, when the gripping plate is operatively assembled with the latter. Extending laterally outward from each side of said chuck member 27 are perforate ears or lugs 33. A detachable clamp plate 34 is 20 provided for binding said gripping plate to said chuck-member. This clamp plate is also provided with lateral perforate ears or lugs 35 to register with the ears or lugs 33 of the chuck member. Fastening bolts 36 are passed through 25 the registered ears or lugs 35—33, thus securing the clamp plate 34 in holding relation to the gripping plate 31. Integral with and dependent from said chuck member 27 is an arm 37. Pivotedly mounted on a cross bolt 38 at and between 30 the outer free ends of the frame side pieces is a dependent swinging lever frame comprising lever bars 39. The lower end of said lever frame is pivotedly connected with the chuck member arm 37 by an interconnecting link 40. Connected 35 with the outer free end portion of the stationary handle member is a slide-piece 41, provided at its under side with a perforate ear 42. Interconnected between said slide-piece ear 42 and the lower free end of said lever frame is a push-bar 43. If desired, means may be provided in 40 association with said slide-piece 41 for cooperating therewith to frictionally grip the end of the stationary handle member for thrusting upon the same without moving the slide-piece relatively 45 thereto. This means comprises a gripper bar 44 movable by hand grasping and squeezing pressure to frictionally bind the intermediate handle member between the same and the slide-piece. To hold the gripper bar 44 in such 50 operative relation to the handle member and the slide-piece, the latter is provided at its end portions with webs 45 extending upwardly through the intermediate space between the bars 23 constituting the handle member, said webs having 55 T-head portions 46 to engage over the top side of said handle bars; the gripper bar 44 is provided on its underside at its ends with lugs 47 to engage and ride in the space between the handle bars 23, said lugs having longitudinal projections 60 48 to underlie portions of said T-heads 46 of the slide piece 41, thereby holding the gripper bar against displacement from assembled relation and yet movable toward and from the handle member and said slide-piece.

65 It is desirable to provide in connection with the stationary handle member and outwardly of the chuck member 27 and its gripping plate 31, an adjustable tie-rod support or rest. This tie-rod support or rest comprises a vertically movable 70 supporting head 49 having a tail piece 50, ver-

tically movable in guideway 51 provided by a guide plate 52 affixed in the space between the handle bars 23. Said guide plate 52 is provided at its lower end with an internally screw-threaded nut piece 53, through which is threaded an adjusting screw 54 to engage the tail piece 50 to thereby vertically adjust the supporting head 49 at desired elevation.

If desired a rod retaining means may also be provided in connection with the stationary handle member intermediate the main frame and the slide piece 41. This retaining means is preferably in the form of a loop or ring 55 having a hinge butt 56 engaged between the handle bars 23 and pivoted thereto by a hinge pin 57. When 15 in use, the loop or ring 55 may be upturned at right angles to the handle member, whereby the end of the tie-rod undergoing extraction may be passed therethrough, so as to be retained thereby against wobbling, undue bending, etc. When 20 not in use, the loop or ring 55 may be folded down upon the top of the handle member, and thus out of the way.

The manner of using the novel tool for a tie-rod extracting operation is as follows:—

The tool may be used either before or after the form walls are stripped away or removed from the face of the cast concrete mass 10; as shown in the drawings, however, the form walls have been removed, leaving the tie-rod 11 with a free end portion thereof projecting outwardly from the face of the concrete mass 10. Before applying the tool to the projecting end portion of the tie-rod 11, the slide-piece 41 is slid on the stationary handle member to its outwardly moved 30 position (shown in full lines in Fig. 1), thereby drawing outwardly the push-bar 43 and thus outwardly swinging the lever frame 39. The outward swinging movement of said lever frame 39 imparts, through the link 40, a like swinging 40 movement to the chuck member 27, whereby the gripping plate 31 carried by the latter is disposed in a vertical position transverse to the longitudinal axis of the tie-rod end to which the tool is to be applied (see full line representation 45 of these parts shown in Fig. 1) so that the rod 11 extends through the chuck member opening and thence freely through the opening 32 of the gripping plate 31. With the tool thus arranged, it is ready for application to the tie-rod end, such 50 application being made by sliding the sleeve or collar 12 of the abutment means onto the rod end until the flange or footing means 13 thereof abuts the outer surface of the concrete mass 10, whereupon the hand lever 18 is upswung to the 55 raised position shown in Fig. 1. Such upswinging of the hand lever 18 swings inwardly the crank lever 17 and draws the frame 19—21 to innermost position. This application of the tool accomplished by utilizing the stationary handle 60 member 23 and push-piece 25 to thrust home the tool to the described position, and the operation can be facilitated by grasping both the slide piece 41 and gripper bar 44 in a squeezing hand grip which will bind the slide piece against movement 65 relative to the stationary handle member, and will thus assist in the thrusting home of the tool. After the tool is thus applied to the tie-rod end, the slide-piece 41 is slid inwardly along the stationary handle member 23, whereby inward motion is imparted to the push-bar 43, which in turn is transmitted to the lever frame 39 and through the link 40 to the chuck-member 27. Such movement swings the chuck member 27 and the gripping plate 31 carried thereby into an ob- 70 75

lique or tilted relation to the tie-rod (as shown by dotted lines in Fig. 1 and by full lines in Figs. 5 and 6). The opening 32 of the gripping plate 31 is slightly larger in diameter than is the diameter of the tie-rod 11, so that, when tilted in the manner described, the sharp peripheral margins or edges 32' of the gripping plate opening 31, respectively at the upper and lower sides thereof, will provide biting edges for strongly gripping the tie-rod. The tie-rod portion projecting outwardly beyond the thus engaged gripping plate is supported by the support or rest 49 so that bending down or distortion of the tie-rod on extracting manipulation of the tool is prevented. With the tool thus operatively engaged with the tie-rod, the hand lever 18 is thereupon swung downwardly and outwardly, in turn swinging outwardly the crank-lever 17 and thereby producing an outward movement of the frame 19-21, which is transmitted to the chuck member 27 and gripping plate 31 carried thereby; such movement being relative to the abutment means 12-13, which is held by its abutment against the surface of the concrete mass 10 against opposite yielding movement. Such outward movement of the frame 19-21 as imparted to the tilted chuck member 27 and gripping plate 31, causes the latter to increasingly and unyieldingly grip the tie-rod, so that an outward longitudinal pulling force is strongly exerted upon the latter, thus loosening the same and starting it outwardly from the concrete mass 10. At the end of the outward stroke thus imparted to frame 19-21, chuck-member 27 and gripping plate 31, the slide-piece 41 is slid outwardly on handle-member 23, thus swinging outward the lever frame 39 and chuck member 27 to release the gripping plate 31 from biting relation to the rod 11, whereupon the hand lever is again swung upward, thus retracting inwardly the frame 19-21 to initial position. When the frame is thus positioned the chuck-member and gripping plate is again tilted to engage the latter in biting relation to the tie-rod, whereupon the operations are repeated to produce another outwardly pulling impulse to the tie-rod. These operations may be repeated to draw out the tie-rod step by step until the same is entirely released from the concrete mass 10, or sufficiently loosened to be directly entirely withdrawn by hand. As the rod is shifted outwardly, its extended end portion may be passed through the guide ring or loop 55, so as to be retained thereby against wobbling or accidental bending or distortion during further manipulation of the tool.

It frequently happens that once a tie-rod is loosened relative to the concrete mass in which it is imbedded, and started outwardly by operation of the tool, the rod may thereafter be entirely withdrawn by directly applied outwardly pulling force. Means are therefore provided for affixing the abutment means 12-13 to the tie-rod so that the tool may be used for such direct hand pulling operation. This means comprises one or more set-screws 58, threaded through a laterally projecting neck 59 provided in connection with the sleeve or collar 12. When this set-screw is tightened, the sleeve or collar 12 is thereby locked to the tie-rod so that direct outward pulling upon the tool is transmitted to said rod.

When the set screw is thus set to lock the sleeve or collar 12 to the tie-rod, the tool may also be turned about its longitudinal axis, thereby to twist the tie-rod in the concrete in aid of loosening the same therein preparatory to rod extracting operations. Another use for the set-screw 58

is to provide means for applying and fixing in the bore of the sleeve or collar 12 bushing sleeves 60 (see Fig. 8) which may be employed to reduce the diameter of the sleeve bore to adapt the same to snug fitting of tie-rods of smaller than maximum diameter receivable therethrough.

In addition to the functioning of the tool as a means for extracting tie-rods from finished concrete, the same may also be used in tightening up forms preparatory to casting concrete. In making the latter use of the tool, the same is applied to a projecting end of a tie-rod, the opposite end of which is suitably anchored, and with the gripping plate 31 engaged to grip or bite the rod, the hand lever 18 is swung down, whereby inward thrusting movement is imparted to the abutment means 12-13, to cause the same to exert inward thrusting pressure upon the form wall structure against which it is abutted. By this operation the form wall assembly is tightened up and held while permanent form holding means are applied and secured, all as is well understood by those skilled in the art of erecting such forms.

Referring to Fig. 7 of the drawings, there is illustrated therein a modified form of means adapted to produce relative movement between the abutment means 12-13 and frame 19-21. This modified arrangement comprises the provision of a longitudinal row of rack teeth 61 upon the exterior of said sleeve or collar 12, with which meshes a toothed quadrant pinion 62, rotatably mounted on the cross-bolt 20 of the frame 19-21, said pinion having a radial neck-portion 63 to which is affixed and from which extends an actuating hand lever 64.

From the above description it will be apparent that a very serviceable and easily manipulated and yet powerful tool is provided for the various purposes above referred to. I am aware that many changes may be made in the above described constructions, and many apparently different embodiments of this invention could be made without departing from the scope thereof; it is therefore intended that all matter contained in the above description and shown in the accompanying drawings shall be interpreted as illustrative and not in a limiting sense.

I claim:

1. In a tool of the kind described, an abutment means having a passage through which a rod may extend, a frame longitudinally movable relative to said abutment means, a stationary handle means extending outwardly from said frame, a rod gripping means pivotally suspended from said frame, means slidably related to said stationary handle means for moving said gripping means into and out of gripping relation to a rod, actuating means interconnected between said abutment means and frame for producing relative movement therebetween, and a handle for said actuating means.

2. In a tool of the kind described, an abutment means having a passage through which a rod may extend, a frame longitudinally movable relative to said abutment means, a stationary handle means extending outwardly from said frame, a rod gripping means carried by said frame, means for moving said gripping means into and out of gripping relation to a rod, means carried by and movable relative to said stationary handle means for operating said means for moving the gripping means, actuating means interconnected between said abutment means and frame for producing relative movement therebetween, and a handle for said actuating means.

3. In a tool of the kind described, an abutment means having a passage through which a rod may extend, a frame longitudinally movable relative to said abutment means, a stationary handle means extending from the lower inner end of said frame outwardly therefrom, a rod gripping means pivotally suspended from said frame, said rod gripping means comprising a chuck-member and a rod gripping plate carried by said chuck-member and having an opening through which a rod may extend, said chuck-member being movable to cant said gripping plate on the rod to engage opposite edges of the plate opening in biting and gripping relation to the rod, means slidably related to said stationary handle means and pivotally connected to the free end of said chuck member for canting the latter, actuating means interconnected between said abutment means and frame for producing relative movement therebetween, and a handle for said actuating means.
4. In a tool of the kind described, an abutment means having a passage through which a rod may extend, a frame longitudinally movable relative to said abutment means, a stationary handle means extending from the lower inner end of said frame outwardly therefrom, a rod gripping means, said rod gripping means comprising a chuck-member and a rod gripping plate carried by said chuck-member and having an opening through which a rod may extend, said chuck-member being movable to cant said gripping plate on the rod to engage opposite edges of the plate opening in biting and gripping relation to the rod, means carried by and movable relative to said stationary handle means for operating said chuck-member and gripping plate, actuating means interconnected between said abutment means and frame for producing relative movement therebetween, and a handle for said actuating means.
5. In a tool as defined in claim 3, a vertically adjustable rod rest carried by said stationary handle means outwardly of said chuck-member and gripping plate.
6. In a tool as defined in claim 4, a vertically adjustable rod rest carried by said stationary

handle means outwardly of said chuck-member and gripping plate.

7. In a tool as defined in claim 3, a rod retaining loop means mounted on said stationary handle means intermediate its free end and said frame.

8. In a tool as defined in claim 4, a rod retaining loop means mounted on said stationary handle means intermediate its free end and said frame.

9. In a tool of the kind described, an abutment means having a passage through which a rod may extend, a frame longitudinally movable relative to said abutment means, a stationary handle means extending from the lower inner end of said frame outwardly therefrom, a chuck-member pivotally dependent from said frame outwardly of said abutment means, a rod gripping plate carried by said chuck-member and having an opening through which a rod may extend, said chuck-member being swingable to cant said gripping plate on the rod to engage opposite edges of the plate opening in biting and gripping relation to the rod, a lever means pivotally dependent from the outer end of said frame, a link interconnecting the lower end of said lever means and the lower end of said chuck-member, a slide means movable on the outward portion of said stationary handle means, a push-bar interconnected between said slide means and said lever means, actuating means interconnected between said abutment means and said frame for producing relative movement therebetween, and a handle for said actuating means.

10. In a tool as defined in claim 9, a vertically adjustable rod rest carried by said stationary handle means outwardly of said chuck member.

11. In a tool as defined in claim 9, a rod retaining loop means mounted on said stationary handle means intermediate its free end and said frame.

12. In a tool as defined in claim 9, a vertically adjustable rod rest carried by said stationary handle means outwardly of said chuck-member, and a rod retaining loop means mounted on said stationary handle means intermediate its free end and said frame.

SAMUEL S. COLT.
